UNITED STATES PATENT OFFICE.

JACOB RIBAYSEN, OF CHICAGO, ILLINOIS.

DESIGN FOR A BRACKET FOR LIGHTING FIXTURES.

Application filed December 22, 1924. Serial No. 11,760. Term of patent 7 years.

To all whom it may concern:

Be it known that I, JACOB RIBAYSEN, a citizen of Russia, residing at Chicago, in the county of Cook and State of Illinois, have invented a new, original, and ornamental Design for Brackets for Lighting Fixtures, of which the following is a specification, reference being had to the accompanying drawing, forming part thereof, in which,—

The figure is a front view of a bracket for lighting fixtures showing my new design.

I claim:

The ornamental design for a bracket for lighting fixtures, as shown.

In witness whereof I have affixed my signature.

JACOB RIBAYSEN.
